UNITED STATES PATENT OFFICE

134,525

DESIGN FOR A BODY FOR A TRAILER VEHICLE OR THE LIKE

James J. Black, Cincinnati, Ohio, assignor to The
Trailer Company of America, Cincinnati, Ohio,
a company of Ohio

Application June 2, 1941, Serial No. 101,260

Term of patent 14 years

To all whom it may concern:

Be it known that I, James J. Black, a citizen of the United States, residing at Cincinnati, in the county of Hamilton and State of Ohio, have invented a new, original, and ornamental Design for a Body for Trailer Vehicles or the like, of which the following is a specification, reference being had to the accompanying drawing, forming a part thereof.

Figure 1 is a side perspective view of a body for a trailer vehicle showing my new design.

Figure 2 is a top plan view thereof.

Figure 3 is a front elevational view thereof.

Figure 4 is a rear elevational view thereof.

Figure 5 is an enlarged fragmentary sectional

view taken on line 5—5, illustrating the shape of the corrugations forming the walls of the vehicle body.

The side of the body opposite to that shown in Figure 1 has the same design as the side shown.

The characteristic feature of my design resides in the vertical corrugated wall portions, the raised portions of which are approximately twice the width of the connecting flat sections.

I claim:

The ornamental design for a body for a trailer vehicle or the like, substantially as shown and described.

JAMES J. BLACK.
